UNITED STATES PATENT OFFICE.

MARCELLUS H. MERRILL, OF NEW LEBANON CENTRE, NEW YORK.

CAR-COUPING.

SPECIFICATION forming part of Letters Patent No. 290,452, dated December 18, 1883.

Application filed May 23, 1883. (No model.)

To all whom it may concern:

Be it known that I, MARCELLUS H. MERRILL, of New Lebanon Centre, in the county of Columbia and State of New York, have invented a new and Improved Car-Coupling, of which the following is a full, clear, and exact description.

The object of my invention is to provide an improved car-coupling of simple and substantial construction, and one which will couple self-actingly on contact of approaching cars, and adapted also for coupling onto the ordinary link-and-pin draw-head, and to be operated without danger to the train-men.

15 The invention consists in a draw-head fitted to slide on the draw-bar, and connected to the latter by a stout pin, working in a slot of the draw-bar, the sliding spring-pressed draw-head having a stout coupling-hook pivoted on one side, and a heavy pin at the other side to be engaged by the coupling-hook of the opposite draw-head. The draw-bar has pivoted to it a trip-lever, which may be set to engage a shoulder at the heel of the coupling-hook, and to be 20 tripped therefrom by the contact of approaching draw-heads when the cars come together, which forces the trip-lever from the coupling-hook shoulder by a pin or stud on the sliding draw-head, thus releasing the hook to fall or 25 be drawn down by its actuating-spring into engagement with the side pin of the opposite draw-head, as will be hereinafter fully described and claimed.

Reference is to be had to the accompanying 35 drawings, forming a part of this specification, in which similar letters of reference indicate corresponding parts in all the figures.

Figure 1 is a side elevation of opposite couplings, with one partly in section, and showing 40 both coupling-hooks held raised by their trip-levers. Fig. 2 is a plan view of the improvement, the opposite draw-heads being coupled; and Fig. 3 is an under side view of one of the couplings, with the hook engaged by the trip-lever.

45 On the draw-bar *a*, arranged for connection to the car-body in any approved way, and preferably formed with the reduced forward end, *b*, forming shoulders *a'*, I fit the sliding draw-head *c*, which has side plates or cheek-

pieces, *c'*, reaching back and lapping the side faces of the bar *a*, the draw-head *c* being recessed at *c*² to fit and slide upon the reduced end *b* of bar *a*, the parts *b c* being held to each other by a stout pin, *d*, which may move in a slot, *e*, of the bar *a* when the draw-head *b* is forced backward against the tension of any suitable spring, *f*, placed preferably between parts *a b* in the recess *c*² of the draw-head. At one side of the sliding draw-head I pivot 60 strongly, at *g*, the coupling-hook *h*, made preferably of cast or untempered steel, and with a heavy or weighted hook-head, *i*, for engaging the strong headed pin *j* of the opposite draw-head, as in Fig. 2, said hook *h* having 65 also a shoulder, *k*, near pivot *g*, to be engaged by the hook arm or pawl *l*, rising from the trip-lever *m*, which is pivoted at *n*, preferably to the under side of the draw-bar *a*, the draw-head *b* being slotted suitably at *b'*, Fig. 3, to move 70 freely past the pivot *n* the short distance required to trip lever *m*. Any suitable stud or pin, *o*, fixed in draw-head *b*, acts against lever *m* to trip it from shoulder *k*, when the draw-head *b* is slid back on the draw-bar *a*, and permit the 75 hook *h* to fall to engage the pin *j* of the opposing draw-head, which hook *h* may drop by its gravity alone; but I prefer to employ any suitable spring, *p*, secured at its opposite ends to the pivot eye or body of the hook and to 80 the draw-head *b*. The spring *p* not only serves to insure the more prompt coupling action of the hook when released from the trip-lever, but holds the coupled hook firmly upon its pin *j*, to prevent noisy chattering of the coupling 85 when the cars are moving, and will also hold the hook *h* against undue swinging action on its pivot *i*, when the coupling-hook hangs head downward and free from pawl *l*, to permit convenient coupling of cars having 90 the ordinary link-and-pin coupling to cars having my improved coupling, which may be done by entering the common link into the socket *r*, (dotted,) which I provide in the draw-head *b*, and passing the common coupling-pin 95 through the holes *s*, made to receive it, and through the link.

To set my improved couplings for automatically coupling the cars, the hooks *h* are raised and the levers *m* swung to engage the hook- 100

shoulders *k*, as in Fig. 1, and when the cars come together the draw-heads *b* will be forced back, the levers *m* will be tripped by studs *o*, and the hooks *h* will instantly fall to engage the headed pins *j* of the opposite draw-head, thus effecting a strong double coupling, whether the cars or their draw-heads are of like or unequal heights, as will readily be understood, the draft-strain being borne entirely by the pins *d j* and the hooks *h*, leaving the trip-levers *m* unaffected thereby.

My improved coupling has few and simple parts, may be cheaply made, and has a positive self-coupling action, making it unnecessary for train-men to pass between the cars when coupling them, and my coupling being of like size with the ordinary link-and-pin draw-head, it may readily be substituted therefor without alteration of the frame-work of the cars.

Having thus described my invention, I claim as new and desire to secure by Letters Patent—

1. A car-coupling constructed with a draw-bar, *a*, sliding spring-pressed draw-head, *c*,

coupling hook and pin *h j*, and lever *m*, to be tripped by the sliding movement of the draw-head, substantially as shown and described.

2. The draw-bar *a*, having reduced end *b* and slot *e*, combined with the spring-pressed draw-head *c*, socketed over end *b*, and having cheek-pieces *c'*, carrying the draft-pin *d*, substantially as shown and described.

3. The combination, with the draw-bar *a*, spring-pressed sliding draw-head *c*, slotted at *b'*, and the coupling-hook *h*, having shoulder *k*, of the lever *m*, pivoted beneath and to the draw-bar, and having pawl *l*, for engaging the shoulder *k* of the hook *h*, substantially as shown and described.

4. The combination of draw-bar *a b*, socketed and slotted sliding head *c c'*, pin *d*, coupling-hook *h i k*, trip-lever *m l*, stud *o*, coupling-pin *j*, spring *p*, link-socket *r*, and pin-hole *s*, substantially as shown and described.

MARCELLUS H. MERRILL.
